No. 664,162.

Patented Dec. 18, 1900.

G. E. LINT.

SASH FASTENER.

(Application filed Oct. 4, 1900.)

(No Model.)

UNITED STATES PATENT OFFICE.

GEORGE E. LINT, OF YORK, PENNSYLVANIA.

SASH-FASTENER.

SPECIFICATION forming part of Letters Patent No. 664,162, dated December 18, 1900.

Application filed October 4, 1900. Serial No. 32,037. (No model.)

To all whom it may concern:

Be it known that I, GEORGE E. LINT, a citizen of the United States, residing at York, in the county of York, State of Pennsylvania, have invented certain new and useful Improvements in Sash-Fasteners, of which the following is a specification, reference being had therein to the accompanying drawings.

This invention relates to sash-fasteners, and particularly to a structure by which one end of a bolt may be retracted within its casing by a spring tension or projected and held beyond the casing under an independent spring tension.

15 The invention has for one object to improve the construction of parts shown in my prior patent, No. 651,464, of June 12, 1900, so as to permit the lock-pin therein to perform all of the functions contemplated in that patent 20 and also to adapt the same to be projected under an independent spring tension in order to automatically lock the window in any raised or lowered position when the pin comes into alinement with a socket therefor.

25 A further object of the invention is to provide a structure involving independent springs, one of which is capable of being placed under tension in order to project and hold the bolt in a direction opposite from that 30 of the retracting-spring.

Other objects and advantages of the invention will hereinafter appear in the following description, and the novel features thereof will be particularly pointed out in the appended claims.

35 In the drawings, Figure 1 is a perspective of a window with the fastener applied thereto. Fig. 2 is a vertical section showing the parts in position to operate as a push-pin to 40 release a locking-catch. Fig. 3 is a vertical section showing the projecting spring under tension in full lines and released by dotted lines. Fig. 4 is a detail perspective of the pin with the retracting-spring removed. Fig. 45 5 is a horizontal section with the parts in the position shown in Fig. 2. Fig. 6 is a detail perspective of the latch, and Fig. 7 is a similar view of one end of the casing.

Like letters of reference indicate like parts 50 throughout the several figures of the drawings.

The letter A designates a latch having a

beveled face A' adapted to contact with the adjoining sash, and thus force the latch backward into its casing until the latch reaches a 55 locking-recess in the adjoining sash. The beveled face of this latch differs from that shown in my prior patent by reason of the bevel upon the face A'. The beveled face herein illustrated extends longitudinally of 60 the latch and also laterally thereof, so that the point of contact with the latch begins at one corner a thereof and gradually increases until the entire lower edge is in contact. (See Fig. 6.) By this means the resistance 65 to the movement of the sash is very slight and the latch easily depressed with the greatest or initial pressure in line with the guide-pin A³, which extends backward from the face A'. This latch is circular in configuration, and thus much more easily applied by 70 simply boring a socket than the rectangular casing, for which the socket must necessarily be mortised. The latch is provided with a flange A², fitting the interior of the casing, 75 and the reciprocation of the guide-pin is limited and controlled by means of a slot A⁴, through which the cross-pin of the casing passes. These features of construction, however, are similar to those disclosed in my 80 former patent. The latch is normally projected outward by means of a spring-latch C', located between the flange A² and the rear wall of the casing C.

The push and lock bolt or pin E is located 85 within a casing F, having at its inner end a collar F' and at its outer end a face-plate F², which may be secured to the casing by any desired means—for instance, lugs F³, passed through apertures F⁴ in the plate F² and bent 90 down thereon. (See Fig. 3.) The pin E is provided at its inner end with a circular portion E', adapted to pass through the collar F', and with an intermediate reduced portion E², 95 around which the coiled projecting spring G is adapted to be located. The retracting-spring H, which normally holds the pin within the casing, as shown in Figs. 2 and 5, bears at one end against the flange E² upon the outer end of the pin and at its opposite end 100 against the collar or shoulder F', so that the tendency of this spring is to draw inward the end E' of the pin. For the purpose of locking the retracting-spring under tension with

the bolt projected a locking-spring H' is provided, which is secured at one end to the pin, and the opposite end H² is bent at an angle and crosses the outer end or face of the pin 5 E. This spring H' is provided with a lock-tooth H³ and a slot H⁴ in the face H², which slot, in connection with a headed pin E⁴, limits the movement of the spring, so that the tooth may be engaged or disengaged from the edge 10 of the aperture in the face-plate F², through which the pin passes. The general structure of the retracting-spring and its connections is similar to that disclosed in my prior patent, with the exception that the locking-spring 15 is simplified in structure to obviate the necessity of the head or cap and permit the same to be formed of a single piece of metal readily secured in position to perform all of the necessary functions in the operation of the device.

The projecting spring G, heretofore described, bears at one end against a shoulder E⁵, formed between the parts E' and E² of the pin, and is connected at its opposite end with 25 a tension-plate G', provided with a locking-tooth G² and a finger-piece G³, by which said tooth may be depressed. The plate G' is located within a groove or recess formed in one face of the pin E, and the locking-tooth is 30 adapted to engage a pivoted contact-plate G⁴, mounted upon the face-plate F², which face-plate is cut away beneath the contact in order to permit a free passage of the locking-tooth G² when the pivoted contact-plate is 35 thrown out of position. It will be seen that if the plate G' be forced inward by means of the finger-piece G³ the tooth G² will engage the rear of the plate G⁴, placing the projecting spring G under tension and normally 40 holding the end E' of the bolt beyond the casting, whereby it will be automatically seated in any socket I into alinement with which it may come. The socket may be formed in any desired manner, but is preferably oval 45 in configuration, as this shape insures a quick and accurate seating of the pin in the socket when the same comes into alinement, particularly if the sash is being rapidly moved.

From the foregoing description it will be 50 seen that the operation of the retracting-spring and locking-spring when the pin is used as a push-pin to release a latch is substantially the same as that disclosed in my prior patent and need not be here enlarged 55 upon. The operation of the novel arrangement of projecting spring, however, is an improvement upon the former patent, by means of which the pin is adapted for use as an automatic locking-pin. When the parts are in 60 the position shown by dotted lines in Fig. 3, it will be seen that if the plate G' be pressed inward and the locking-tooth engaged behind the contact-plate G⁴ the spring G may be placed under a tension greater than that of 65 the spring H and the end E' of the bolt projected. The parts are then in the position shown by full lines in Fig. 3, whereby the

projecting spring bears at one end against the shoulder E⁵ of the bolt and at the opposite end a fixed contact is secured by means of the connection of the plate with the face-plate F². When the end E' of the pin travels in contact with the face of the sash, the spring will be compressed and the outer or pushing end thereof forced backward into the position shown by dotted lines, but as soon as the end E' comes into alinement with the socket I the tension of the spring projects the end of the pin into the position shown by full lines and locks the sashes together. By a proper disposition of the sockets the upper sash may be lowered any desired distance for ventilation and locked in such position, or the co-operating sashes may be secured together in any other desired relation. In this connection it may be stated that if the contact-plate G⁴ be raised the tension of the projecting spring G is immediately released and the retracting-spring H at once acts to withdraw the pin from the socket, and if it be desired to lock the pin in the socket the same may be accomplished by means of the locking-spring H', as described in my prior patent. The present invention therefore presents in a single device a push and lock pin or bolt capable of the several functions heretofore attained by independent devices, and thus renders the apparatus capable of use in a variety of different methods, dependent upon the wishes of the occupant of the premises.

It is obvious that changes may be made in the details of construction and configuration of the several parts without departing from the spirit of the invention as defined by the appended claims. As shown in Fig. 4, the retracting-spring may be omitted from the bolt and the same used as a sliding bolt or a spring-actuated bolt. The several parts of the projecting spring and the plate for placing the same under tension are capable of action independently of the retracting-spring, which has been herein disclosed as associated therewith.

Having described my invention and set forth its merits, what I claim as new, and desire to secure by Letters Patent, is—

1. A sash-fastener comprising a casing open at opposite ends, a pin adapted to be extended beyond either end of the casing, a retracting-spring adapted to move one end of said pin toward said spring, and an independent projecting spring adapted to be placed under tension to project an end of said pin away from said retracting-spring; substantially as specified.

2. A sash-fastener comprising a casing open at opposite ends, a pin adapted to be extended beyond either end of the casing, a retracting-spring adapted to move one end of said pin toward said spring, an independent projecting spring adapted to be placed under tension to project an end of said pin away from said retracting-spring, and means engaging one end of the casing for placing said projecting

spring under tension and releasing said tension; substantially as specified.

3. A sash - fastener comprising a pin, a spring for projecting the same, a fixed plate, 5 and means for engaging and disengaging one end of said spring from said plate; substantially as specified.

4. A sash - fastener comprising a pin, a spring for projecting the same, a fixed plate, 10 and a tension-plate carried by said spring and provided with a tooth adapted to engage a fixed contact - plate; substantially as specified.

5. A sash - fastener comprising a pin, a spring for projecting the same, a tension-plate 15 connected to one end of said spring and slid- ingly mounted upon one end of said pin, a tooth carried by said plate, a fixed plate hav- 20 ing a recess in alinement with said tooth, and a contact-plate pivoted to move over and close 25 said recess; substantially as specified.

6. A sash - fastener comprising a pin, a spring for projecting the same, a tension-plate 25 connected to one end of said spring and slid- 30 ingly mounted upon one end of said pin, a tooth carried by said plate, a fixed plate hav- 35 ing a recess in alinement with said tooth, a contact-plate pivoted to move over and close 40 said recess, and a locking-spring secured to 45 said pin and provided with a tooth adapted to engage said fixed plate; substantially as specified.

7. A sash - fastener comprising a pin, a spring for projecting the same, a tension-plate 35 connected to one end of said spring and slid- 40 ingly mounted upon one end of said pin, a tooth carried by said plate, a fixed plate hav- 45 ing a recess in alinement with said tooth, a contact-plate pivoted to move over and close 50 said recess, a locking-spring secured to said 55 pin and provided with a tooth adapted to en- gage said fixed plate, a casing provided with a shoulder at one end, and a retracting-spring located between said shoulder and a shoulder upon said pin; substantially as specified.

8. A sash-fastener comprising a pin, a spring for projecting the same, a tension-plate connected to one end of said spring and slid- 50 ingly mounted upon one end of said pin, a tooth carried by said plate, a fixed plate having a recess in alinement with said tooth, a contact-plate pivoted to move over and close said recess, a locking-spring secured to said pin and provided with a tooth adapted to engage said 55 fixed plate, a casing provided with a shoul-

der at one end, a retracting-spring located be- 60 tween said shoulder and a shoulder upon said pin, a slotted plate carried by said locking- 65 spring, and a stop-pin carried by one end of said pin to limit the movement of said plate; substantially as specified.

9. A sash-fastener comprising a sliding bolt, a casing therefor, a retracting-spring bearing against said casing and bolt, a locking-spring secured to one end of said bolt, and provided 70 with an angularly-disposed slotted plate, a tooth carried by said spring and adapted to engage a fixed part, and a stop projecting from the end of said bolt through said plate; substantially as specified.

10. In a sash-fastener, the combination of a casing, a face-plate therefor, a bolt within said casing provided with a shoulder, a re- 75 tracting-spring extending between said shoul- 80 der and a shoulder of the casing, a locking- 85 spring carried by said bolt and having a tooth adapted to engage said face-plate, a project- 90 ing spring adapted to bear at one end against a shoulder at the operating end of said bolt, a tension-plate connected to the opposite end 95 of said spring and provided with a tooth, and means for engaging and holding said tooth to place said projecting spring under tension; substantially as specified.

11. In a sash-fastener, the combination of 85 a casing, a face-plate therefor, a bolt within said casing provided with shoulders at op- 90 posite end portions, a retracting-spring ex- 95 tending between one shoulder of the bolt and a shoulder at the opposite end of the casing, a locking-spring carried by said bolt and hav- 100 ing a tooth adapted to engage said face-plate, a projecting spring adapted to bear at one end against the shoulder at the operating end of the bolt, a tension-plate slid- 105 ingly mounted in a recess in said bolt and connected to the opposite end of said spring, a tooth carried by said plate nearer the center of the bolt than the tooth upon the locking-spring, and a piv- 110 oted contact-plate carried by said face-plate and adapted to close a recess in said face-plate and engage the tooth of said tension-plate to place the projecting spring under tension, substantially as specified.

In testimony whereof I affix my signature 105 in presence of two witnesses.

GEORGE E. LINT.
